UNITED STATES PATENT OFFICE

163,692

AUTOMOBILE HOOD ORNAMENT

Ervin C. Gubler, Salt Lake City, Utah

Application May 31, 1949, Serial No. 2,971

Term of patent 14 years

(Cl. D14—18)

To all whom it may concern:

Be it known that I, Ervin C. Gubler, a citizen of the United States and a resident of Salt Lake City, county of Salt Lake, and State of Utah, have invented a new, original, and ornamental Design for an Automobile Hood Ornament, of which the following is a specification, reference being had to the accompanying drawing, forming part thereof.

In the drawing, which shows my new design for an automobile hood ornament, photographically, the fragmentary inclusion of the automobile hood is for illustrative purposes only; thus,

Fig. 1 represents a front elevation of the automobile hood ornament, showing my new design;

Fig. 2, is a side elevation; and
Fig. 3, a view in perspective.

I claim:

The ornamental design for an automobile hood ornament, as shown, and described.

ERVIN C. GUBLER.
